TRACTION DEVICE FOR A SNOW THROWER OR SIMILAR ARTICLE

Robert W. Dickgiesser, Bloomington, Minn., assignor to
Toro Manufacturing Corporation, Minneapolis, Minn.

Filed Mar. 22, 1971, Ser. No. 127,090

Term of patent 14 years

Int. Cl. D15—03, 99

U.S. Cl. D35—2

FIG. 1

FIG. 2

FIG. 3

FIG. 4

FIG. 5

FIG. 1 is a perspective view of one preferred embodiment of a traction device for a snow thrower or similar article as viewed from the outer side thereof;

FIG. 2 is a perspective view thereof as seen from the inner side thereof;

FIG. 3 is a side elevational view thereof as seen from the outer side;

FIG. 4 is a side elevational view thereof as viewed from the inner side; and

FIG. 5 is an end elevational view thereof.

I claim:

The ornamental design for a traction device for a snow thrower or similar article, substantially as shown.
